Patented Oct. 26, 1971

222,481

COMBINED BIRD WATERING FOUNTAIN AND HUMMING BIRD FEEDER

Robert Rakowski, 3411 Rosalie Ave.,
Baltimore, Md. 21234

Filed Dec. 10, 1970, Ser. No. 26,394

Term of patent 14 years

Int. Cl. D30—03

U.S. Cl. D30—14

FIG. 1

FIG. 2

FIG. 3

FIG. 4

FIG. 1 is a side elevational view of a combined bird watering fountain and humming bird feeder showing my new design;

FIG. 2 is a front elevational view thereof, a portion sectioned for illustrative purposes;

FIG. 3 is a top plan view thereof;

FIG. 4 is a bottom plan view thereof.

I claim:

The ornamental design for a combined bird watering fountain and humming bird feeder, as shown and described,
